UNITED STATES PATENT OFFICE

JOHN SNEED, OF DETROIT, MICHIGAN, ASSIGNOR TO THE MIDLAND STEEL PRODUCTS COMPANY, OF CLEVELAND, OHIO, A CORPORATION OF OHIO

BRAKE MECHANISM

Application filed August 1, 1927. Serial No. 209,686.

This invention relates to brakes and more particularly to the shoe structure and adjusting means therefor.

It is among the objects of my invention to provide a brake assembly including a brake shoe which may be economically manufactured and assembled, which can be readily and easily adjusted without affecting the characteristics which are inherent to the shoe.

10 Another object is to form an annular shoe of two pieces and join them together by means which also permit adjustment of the total shoe length. Another object is to form an annular shoe which acts as one piece and 15 which is channel shaped at its adjacent ends. Another object is to secure the adjusting means in the shoe in a manner which will not detract from flexibility or resiliency of the shoe at that point.

20 Another object is to position the adjusting means with relation to the cross section of the shoe so that the increase or decrease in the length of the shoe occasioned by adjusting will not distort the contour of the shoe. 25 Another object is to provide a shoe, which both at its anchorage and throughout its length will be free from angular or lateral distortion when in operation.

Other objects will appear from the following description of the drawings disclosing a 30 preferred form of my invention. The essential characteristics are summarized in the claims.

In the drawings, Fig. 1 is an elevation of 35 the assembly; Fig. 2 is a section taken along the line 2-2 in Fig. 1; Fig. 3 is a section taken along the arcuate line 3-3 in Fig. 1; Fig. 4 is an illustrative channel section taken along either of the lines 4-4 in Fig. 1; Fig. 40 5 is a cross section taken along the line 5-5 in Fig. 3; and Fig. 6 is a section taken along the line 6-6 in Fig. 3.

Referring particularly to Fig. 1, I illustrate a brake drum D in which is mounted a 45 brake shoe S. The shoe S comprises two parts, one part is channelled in cross section throughout its length, as shown in Fig. 4. The channel flanges are, in the preferred form, of progressively decreasing depth from 50 the point of anchorage throughout that part

of the shoe. The shoe also consists of a portion 2 which is only partly channelled in section, having a cross section similar to the cross section of the portion 1 of the shoe at the point of anchorage. The major portion 55 of the part 2 comprises a curved band which extends around and meets the end of the channelled part 1 of the shoe. Suitable brake lining L is carried on the lining supporting surface of the shoe.

An anchor pin A is shown positioned between the free ends of the shoe and may be circular in cross section. Both side flanges of the channelled ends of the shoe may abut this anchor pin as at 5 and 6 so that either 60 end of the shoe may anchor on a pivotal bearing surface with the anchor pin. The anchor pin may be suitably supported by a backing plate, not shown. A spring G is provided to normally draw both ends of the shoe 65 into engagement with the anchor pin and out of engagement with the drum. Positioned adjacent the anchor pin, I provide a shoe expanding means (see also Fig. 2), comprising a toggle 10 which may be actuated by a 70 cable 11 or other suitable means. The toggle has universal connections with both ends of the shoe through the pins 12 and 13, which are pivotally mounted in the side flanges of the shoe. The toggle in turn has a pivotal 75 engagement with the small pins 14 and 15 extending through the major pins 12 and 13.

To adjust the length of the shoe to compensate for wear, I have devised means illustrated in Figs. 1, 3, 5 and 6. This adjusting device comprises a flat curved member 20 which may advantageously have the same characteristics of flexibility and resiliency as the flat curved portion of the part 2 of the shoe and may be secured to the end of 80 the part 2 of the shoe by suitable means, such as rivets 21. The member 20 may have a small upwardly curved tail piece 22 to which a spring 23 may be secured. The member 20 serves to join the parts 1 and 2 of 85 the shoe together and extends over and lies upon the lining supporting portion of the part 1 of the shoe (see Fig. 5). The part 1 of the shoe is preferably originally formed to be entirely channelled in section and end 90 100

pieces of the side flanges in the channel are overturned as at 25 (see Figs. 3 and 5) to form inwardly facing grooves in which the member 20 is held in firm but slideable engagement. The inturned side flanges hold the member 20 against both lateral and radial movement. The end of the member 20 is beveled as at 26 and may be forced outwardly of the part 1 of the shoe by wedge block 27, which has a lower face formed complementary to the edge 26 of the member 20. The wedge block is in threaded engagement with the screw 30, which is seated against one of the side flanges of the part 1 of the shoe, as at 31, and which is journaled in the other side flange, as at 32. A square head 33 or other suitable means are provided for turning the screw 30.

The wedge block may have an extension 28 to which the other end of the spring 23 is secured so that the wedge block is normally urged counter-clockwise onto the member 20 as at 29, maintaining the beveled surface of the block in engagement with the beveled surface of the member 20. The spring 23 also tends to hold the ends of the separate parts of the shoe together and to force the member 20 against the wedge block.

It will appear from the foregoing that I have provided a substantially annular and integral shoe brake, which shoe is adjustable within itself and has all the characteristics of a single piece shoe. It will further appear that such a shoe can be readily formed and quickly assembled, and that the whole shoe may be quickly assembled in the brake drum and thereafter readily adjusted to any desired length.

Various modifications of this invention will appear to one skilled in the art without departing from the spirit thereof. I do not care to be limited in the scope of my invention other than by the claims appended hereto.

45 I claim:—

1. A brake shoe having a channelled part, with side flanges and a lining supporting portion, and a flat curved part, the flat curved part having an extension overlying the lining supporting portion of the channel part, the side flanges of the channel part being inturned to engage the extension of the flat curved part.

2. A brake shoe having a channel part with side flanges and a lining supporting portion and a flat curved band like part of greater flexibility than the channel part, the flat curved part having an extension overlying the lining supporting portion of the channel part, and secured between the side flanges of the channel part.

3. A brake shoe having a part channelled in cross section with inwardly extending radial side flanges and a curved lining supporting portion, the ends of the side flanges

being inturned to form oppositely facing grooves, and a member lying upon said lining supporting portion and engaged between said grooves.

4. A brake shoe member being channelled in cross section and having inwardly extending radial side flanges of progressively decreasing depth from substantially one end to the other, the side flanges of least depth being inturned to form oppositely facing grooves at one end of the member. 70

5. A brake shoe having a part channelled in cross section with inwardly extending radial side flanges and a curved lining supporting portion, the side flanges being inturned to form oppositely facing grooves at one end and being shaped to form an anchor bearing surface at the other end. 80

6. A brake shoe being channelled in cross section and having inwardly extending radial side flanges of progressively decreasing depth from substantially one end to the other, the side flanges of least depth being inturned to form oppositely facing grooves at the end, said flanges being shaped to form anchor bearing surfaces at the other end. 90

7. A substantially annular brake shoe comprising separable parts joined together end to end, one of said parts being channelled in cross section, the other part being essentially flat and curved. 95

8. A brake shoe having a flat curved part and a channelled-shaped part, the parts abutting end to end, and means fixed to one of the said parts and adjustably secured to the other for joining said parts. 100

9. A brake shoe having a flat curved part and a channel shaped part, the parts abutting end to end, and means fixed to the said flat curved part and adjustably secured to the other part for joining said parts together. 105

10. A brake shoe comprising a part channelled in section, having inwardly extending radial side flanges and a lining supporting portion, said shoe also comprising another part having an extension lying between the radial side flanges of the first named part, and means including a screw journaled in the said side flanges for positioning said extension relative to said first named part. 110

11. A brake shoe comprising a part channelled in section, having inwardly extending radial side flanges and a lining supporting portion, said shoe having another part with an extension between the radial side flanges of the first named part, and means including a wedge and a screw journaled in the said side flanges for positioning said extension relative to said first named part. 120

12. A brake shoe having a channelled part with inwardly extending radial side flanges and another part having an extension lying between said radial flanges, the ends of said flanges being inturned to engage said ex- 130

tension, said extension having a beveled end and means including a wedge block bearing against the end of said extension for adjusting said extension relative to said first named part.

13. A brake shoe having a channel part with inwardly extending radial side flanges and another part having an extension lying between said radial flanges, the ends of said flanges being inturned to engage said extension, said extension having a beveled end and means including a wedge block bearing against the end of said extension for adjusting said extension relative to said first named part, and a screw journaled in the radially extending portion of said side flanges for actuating said wedge.

14. A brake shoe comprising two parts adjustably joined together, and extension member fixed to one part and having inwardly extending tail piece, said extension member having a beveled end and being in engagement with the other part, a wedge block engaging the beveled end of said extension member and overlying it, said wedge block having an inwardly extending piece and a spring connected to said piece and to the tail piece of said extension member.

15. A brake shoe comprising two parts adjustably joined together, and extension member fixed to one part and having a beveled end and overlying the other part, a wedge block engaging the beveled end of said extension member and overlying it, said wedge block having an inwardly extending piece, and a spring connected to said piece for holding the block in engagement with said extension member.

16. A substantially annular brake shoe partly channeled in cross section and being of progressively decreasing flexibility from a point near the middle throughout said channeled part to one end, and means positioned remote from the ends of the shoe at said point for adjusting the length of the shoe.

17. A substantially annular brake shoe of progressively decreasing flexibility from a point near the middle to one end, and means positioned remote from the ends of the shoe at said point for adjusting the length of the shoe.

18. A brake shoe formed substantially as a split ring and comprising two parts, one part being flexible relative to the other part and means adjustably secured to one part for joining the parts together.

19. A brake shoe formed substantially as a split ring and comprising two parts, one part being flexible relative to the other part and means fixed to the relatively flexible part and adjustably secured to the other part for joining the parts together.

20. A brake shoe having a part channeled in cross section with inwardly extending ra-

dial side flanges and a curved lining supporting portion, the ends of the side flanges being inturned to form oppositely facing grooves, a member lying upon said lining supporting portion and engaged between said grooves, and means for positioning said member longitudinally of the channeled part.

21. A brake shoe having a part channeled in cross section with inwardly extending radial side flanges and a curved lining supporting portion, the ends of the side flanges being inturned to form oppositely facing grooves, a member lying upon said lining supporting portion and engaged between said grooves, and wedging means for positioning said member longitudinally of said grooves.

22. A brake shoe formed substantially as a split ring comprising a relatively rigid part and a relatively flexible part, and means interposed between said parts for adjusting the length of the shoe.

23. A substantially annular brake shoe comprising separable parts joined together end to end, one of said parts being relatively rigid and the other of said parts being relatively flexible.

24. A brake shoe comprising two separable parts joined together end to end, one of said parts having inwardly extending reinforcing means rendering it relatively rigid, the other of said parts being essentially flat and curved and relatively flexible.

In testimony whereof, I hereunto affix my signature.

JOHN SNEED.
